LASTING MACHINE

Bernhardt Jorgensen, Marblehead, Mass., assignor to United Shoe Machinery Corporation, Flemington, N. J., a corporation of New Jersey

Application October 24, 1950, Serial No. 191,787

23 Claims. (Cl. 12—10.5)

1

This invention relates to lasting machines and is herein shown as applied to a power-operated toe-lasting machine constructed generally as disclosed in United States Letters Patent No. 2,324,509, granted on July 20, 1943, on an application of mine, but modified in some respects in accordance with later disclosures including that of a copending application of mine Serial No. 134,041, filed on December 20, 1949. It is to be understood, however, that in various novel aspects the invention is not thus limited in its applicability.

The machine to which the invention is shown as applied is a machine in which various mechanisms are operated by fluid, preferably light oil, maintained under pressure in a manifold from which the fluid is admitted by valves to the different mechanisms, the fluid being thus maintained under pressure while the machine is in operation by a continuously driven pump and the maximum pressure in the manifold being determined by a spring-controlled relief valve. The machine includes a toe rest arranged to engage a shoe on the top of the forepart to support the shoe against pressure applied on its bottom face, and also a heel rest for engaging the heel-end face of the shoe and holding it against lengthwise displacement in a heelward direction in the lasting operation, the toe rest and the heel rest being forced firmly against the shoe by the fluid pressure. While the pressure applied to the shoe by the toe rest or the heel rest should be sufficient to prevent any displacement of the shoe, it should not be great enough to mark the upper, the pressure which may be safely applied depending somewhat upon the character of the upper materials. To meet different conditions the present invention provides means whereby the pressure of the fluid effective on either the toe rest or the heel rest may be variably predetermined independently of the pressure effective on the other and independently of the pressure at the source, i. e., in the manifold. For this purpose there is interposed in each fluid line leading from the manifold to the means for operating the toe rest or the heel rest pressure-controlling mechanism including a cut-off valve and a spring-controlled member movable in response to the pressure of the fluid effective on the toe rest or the heel rest to close this valve and stop the flow of the fluid when that pressure reaches a predetermined limit, the spring controlling this member being adjustable to vary that limit. This member is so arranged that any force applied to the shoe in the lasting operation tending to press the shoe more firmly against

5 the toe rest or the heel rest only serves to hold the corresponding cut-off valve more firmly closed, thus insuring that the shoe will be firmly held against any displacement.

10 2 The machine is provided with wipers which wipe the margin of the toe end of the upper inwardly over an insole on a last positioned bottom upward, and with upper-trimming means movable in a plane parallel to the top faces of the wipers to remove from the margin of the upper supported in outspread position on the wipers all but the outer layer of the upper materials before the upper is thus wiped inwardly over the insole. Preparatory to the upper-trimming operation a wiper support is moved upwardly to carry the wipers to a predetermined height relatively to the edge of the insole while the upper is being pulled outwardly over the wipers by grippers engaging the margin of the upper materials, the upper-trimming means being moved downwardly into proper relation to the wipers for the trimming of the upper as above described. After the trimming of the upper the wiper support is moved downwardly and then moved upwardly a second time, coordinately with a second pull applied to the upper by the grippers, preparatory to the wiping of the margin of the upper inwardly over the insole. Heretofore the wipers have been positioned at such a height in the upper-trimming operation that a margin of about an eighth of an inch is left on the trimmed layers of the upper materials to overlap the bottom face of the insole when the upper is wiped inwardly over the insole, this being the height at which the wipers are also positioned by the second upward movement of the wiper support for the wiping of the upper inwardly over the insole. Some manufacturers, however, would prefer that a margin of somewhat greater width be left on the trimmed layers of the upper materials to overlap the insole, but if the wipers are positioned at the height required for this result in the upper-trimming operation, they should not be moved to the same height by the second upward movement of the wiper support, since in that case they would be too high to act most effectively on the upper in wiping it inwardly. In view of these considerations the machine herein shown is provided with means whereby the wipers may be moved to a greater height by the first upward movement of the wiper support than by its second upward movement, the limit of the downward positioning movement of the upper-trimming means being correspondingly changed. In the machine shown both upward movements of the wiper support are effected, as heretofore,

by a pair of pistons having invariable limits of upward movement and having pin-and-slot connections with the support, and the difference between the limits of the different movements of the wiper support results from the shifting from one position to another of a link included in the connections between the support and one of the pistons. More particularly, this link is provided with a slot so formed that as a result of such shifting of the link the second upward movement of the support is terminated short of the limit of its first upward movement. For thus shifting the link there is provided a latch which is idle in the first upward movement of the wiper support but is thereafter moved into position to cause it to shift the link in response to the second upward movement of the support. To cause the wipers alternatively to be moved, if desired, to the same height by the first upward movement of the wiper support as by its second movement, so that a margin of less width will be left on the trimmed layers of the upper materials to overlap the insole, a manually operated member is provided for maintaining the latch in position to swing the link in response to both upward movements of the wiper support, connections being provided between this member and means for effecting a corresponding variation in the downward movement of the upper-trimming means. The machine is thus provided with means for quickly varying at will the width of the margin left on the trimmed layers of the upper materials to overlap the bottom face of the insole.

The above-mentioned wiper support further carries, as heretofore, a toe former which, in response to each upward movement of the support, wipes the upper around the toe end of the last heightwise of the last while the upper is held under tension by the upper-gripping and pulling means. It will be evident that when the wiper support is moved upward a greater distance the first time in the manner above described, the toe former has a more extended wiping action on the upper in the vicinity of the edge of the insole. This has been found to contribute to the smoothness of the upper adjacent to the edge of the insole in the completed shoe and is accordingly advantageous regardless of considerations relating to the trimming of the upper.

In general accordance with the disclosure of Letters Patent No. 2,479,575, granted on August 23, 1949, on an application of mine, the above-mentioned pin-and-slot connections between the wiper support and the pistons which operate it permit the support to be moved farther upward relatively to the pistons against the force of gravity in response to resistance of the upper to the inward movements of the wipers over the insole. This prevents the wipers from acting too severely on the margin of the upper as they otherwise might under some conditions. After the wipers have wiped the upper inwardly over the insole the pistons are operated to increase their downward pressure on the upper and are then returned to their upper limits of movement to relieve the pressure. In accordance with a further feature the invention provides means whereby the margin of the upper is substantially released at this time from any pressure of the wipers thereon. In the construction shown this is accomplished by substantially eliminating at the required time lost motion between one of the pistons and the wiper support, so that such movement as the piston receives in relieving the pressure of the wipers on the upper will be transmitted to the support to raise the wipers. More

particularly, the wiper support carries a member which, as the pistons are moved downwardly to increase the pressure of the wipers on the upper, is moved by a spring into such relation to a pin carried by one of the pistons as to transmit movement from the pin to the wiper support upon upward movement of the piston. The means for thus substantially releasing the shoe from downward pressure of the wipers thereon is of special advantage in the machine herein shown by reason of the presence of the previously mentioned pressure-controlling mechanism in the fluid line leading to the toe rest. As previously explained, this mechanism includes a cut-off valve which is held more firmly closed by any increase in downward pressure applied by the shoe to the toe rest. The timing of the machine is such as to call for release of the toe rest by the fluid acting thereon to cause it to return to its initial position prior to the retractive movements of the wipers from over the shoe, and accordingly the provision of the above-described means for substantially releasing the toe end of the shoe from the pressure of the wipers thereon while the wipers are over the shoe insures that the above-mentioned cut-off valve will not be prevented from opening at the time in the cycle when the return of the toe rest is supposed to take place.

The above and other features of the invention, including various novel details of construction and combinations of parts, will now be more particularly described with reference to the accompanying drawings and thereafter pointed out in the claims.

35 In the drawings,

55 Fig. 6 is a view partly in right-hand side elevation and partly in section of a portion of the structure shown at the left-hand side of Fig. 2;

Fig. 7 is a plan view of means for variably limiting the downward movement of the upper-trimming means;

55 Figs. 8, 9 and 10 are views in vertical section illustrating the relation of certain parts to the shoe at different times in the operation of the machine; and

60 Fig. 11 is mainly a diagrammatic view illustrating the character of the fluid-pressure system and its relation to certain parts operated by the fluid pressure.

65 In view of the above-mentioned prior disclosures, only as much of the machine will be herein described in detail as is necessary for an understanding of the invention. The shoe is presented to the machine bottom upward and is positioned heightwise by engagement of a shoe-rest plate 2 (Fig. 8) with the bottom of the forepart of the insole. It is clamped against this plate substantially at the beginning of the operation of the machine by an upwardly movable toe rest 4 which engages the shoe underneath on the top of the forepart and is forced firmly against the shoe by a fluid-operated piston 6 (Fig. 11) movable in a cylinder 8. Operating fluid, preferably

light oil, under pressure is admitted to this cylinder through a pipe line 10 from a manifold 12 in which the fluid is maintained under pressure during the operation of the machine by a pump 14. The pump receives fluid through a pipe 16 from a sump 18 and forces it into the manifold through a pipe 20, the maximum pressure of the fluid in the manifold being determined by a spring-controlled relief valve 22 past which the excess fluid returns to the sump through a pipe 24. Admission of the fluid from the manifold to the pipe line 10 leading to the cylinder 8 is effected by an automatically operated valve 26 which, near the end of the cycle, is moved to exhaust position to release the fluid from the cylinder 8 and permit it to return to the sump. In addition to the toe rest 4 the machine includes a heel rest 28 for engaging the heel end face of the shoe to assist in preventing its lengthwise displacement in a heelward direction in the lasting operation, this heel rest being applied to the shoe and forced firmly against it by a piston 30 movable in a cylinder 32 to which fluid is admitted through a pipe line 34 from the manifold 12 under control of a valve 36 operating similarly to the valve 26. The heel rest is supported on a carrier 38 which is mounted for swinging movement about a rod 40 and is connected to the piston 30 by a link 42.

The pressure applied by the toe rest 4 to the shoe should be sufficient to support the toe end of the shoe against any downward movement in response to pressure on the bottom of the shoe in the lasting operation, and yet must not be great enough to mark the upper. Similarly, the pressure of the heel rest 28 on the heel-end face of the shoe should be sufficient to insure against any lengthwise displacement of the shoe in a heelward direction by the lasting means, and yet must not be so great as to mark the upper or to damage a hinge last. The pressure which may be applied by either the toe rest or the heel rest without marking the upper will depend to some extent on the character of the upper materials. In view of these considerations, the machine herein shown is provided with means whereby the pressure of the fluid effective on either the toe rest or the heel rest may be variably predetermined independently of the pressure of the fluid effective on the other and also independently of the pressure of the fluid effective to operate other parts of the machine. For this purpose there is interposed in each of the pipe lines 10 and 34 (Fig. 11) a pressure-controlling device 44, the parts of both devices being identical and identified by the same reference characters. Each device includes a casting 46 having in one end thereof a chamber 48 to which fluid is admitted from the manifold 12. Also formed in the casting is a cylinder 50 in which is mounted a piston 52. Between the chamber 48 and the cylinder 50 the casting 46 has formed thereon an inwardly extending annular flange 54 which provides a passageway through which the fluid may flow from the chamber to the cylinder. A stem 56 extends from the piston 52 through this passageway but is smaller than the passageway to permit the flow of the fluid, and fast on the end of this stem is a cut-off valve 58. Confined between the piston 52 and an abutment 60 is a spring 62 which tends to move the piston toward the flange 54, its movement in that direction being limited by engagement of a spider 64 formed on the stem 56 with the flange. The spring 62 is adjustable to vary its compression

by a screw 66 which is threaded in the plug 68 in the casting 46 and engages the abutment 60. A port 70 in the casting provides open communication between the portion of the casting in which the spring 62 is mounted and the atmosphere. Another port in the casting provides communication between the cylinder 50 and the portion of the pipe line 10 or 34 leading to the cylinder 8 or 32. With the parts positioned initially as shown the valve 58 is open and permits fluid to flow from the chamber 48 to the cylinder 50 and thence to the cylinder 8 or 32 when the corresponding valve 26 or 36 is operated. As soon as the fluid pressure effective on the toe rest or the heel rest becomes great enough to overcome the force of the spring 62 the piston 52 is moved into position to seat the valve 58 on the flange 54 and thus to stop the flow of fluid from the chamber 48 to the cylinder 50. In this manner the pressure of the fluid effective on the toe rest or the heel rest is limited, in accordance with the adjustment of the corresponding spring 62, independently of the pressure of the fluid effective on other parts of the machine, and it will also be evident that the pressure applied by either the toe rest or the heel rest to the shoe is thus variably predetermined independently of that applied by the other. It will be further evident that any force applied to the shoe in the lasting operation and tending to press the shoe more firmly against the toe rest or the heel rest only serves to hold the corresponding valve 58 more firmly closed by reason of the increase in the pressure of the fluid effective on the corresponding piston 52, thus insuring that the shoe will be firmly held against any displacement. When the valve 26 or 36 is moved to exhaust position the release of the pressure in the chamber 48 which results from such movement of the valve causes the spring 62 to move the corresponding valve 58 to open position and thus to release the fluid in the cylinder 8 or 32.

In general accordance with the prior disclosures the machine is provided with a toe-end gripper 72 which grips the margin of the upper at the end of the toe and with opposite side grippers, not herein shown, which grip it at the sides of the toe, the end gripper and the side grippers being movable respectively in directions mainly lengthwise and widthwise of the shoe to apply a pull to the upper. The machine also includes a pair of toe-embracing wipers 74 (Figs. 2 and 8) for wiping the margin of the upper inwardly over an insole on the last and a toe former 76 (Figs. 2, 3 and 8) positioned immediately under the wipers for wiping the upper around the toe heightwise of the last, the toe former and the means for controlling it being constructed substantially as disclosed in the previously mentioned application. As disclosed in detail in Letters Patent No. 2,324,509, the wipers are mounted on wiper holders 78 (Figs. 2 and 3), these wiper holders being mounted on a wiper carrier 80 movable in directions lengthwise of the shoe relatively to a member 82 on which it is mounted and which may be termed a wiper support. The wiper carrier 80 is moved forwardly lengthwise of the shoe by fluid-pressure means and in response to such movement of the carrier the wiper holders 78 and the wipers are swung about a vertical axis to cause the wipers to close inwardly over the insole widthwise of the shoe.

The wiper support 82 is mounted as heretofore for upward and downward movements and

by such movements carries the wipers and the toe former with it as a unit, the toe former being arranged to wipe the upper heightwise of the last in response to the upward movement of the support while the grippers are applying their pull to the upper. In thus pulling the upper the grippers in the first instance grip the several layers of upper materials, usually including at least a toe box and a lining in addition to the outer layer, and at the end of the upward movement of the wiper support they hold the marginal portion of the upper outspread over the top faces of the wipers. Thereafter the upper is operated upon by trimming means 84 (Fig. 1) to remove from its margin over the wipers all but the outer layer of the upper materials, as illustrated in Fig. 8, the grippers releasing the upper prior to the completion of the upper-trimming operation. This upper-trimming means includes an end knife 86 movable lengthwise of the shoe in a rearward direction from an initial position over the bottom of the shoe and a pair of side knives 88 movable outwardly widthwise of the shoe from over the bottom of the shoe. The end knife is carried by an arm 90 which is swung downwardly to position its cutting edge in the same plane as the edges of the side knives 88 before it becomes effective on the upper, and associated with each side knife is a vertical knife 92 arranged to detach from the rest of the upper the strip resulting from the action of the knives 86 and 88.

The upper-trimming means 84 is supported on a carrier 94 which is fast on a post 96 mounted for vertical movements and for turning movements in the frame of the machine, this post being moved downwardly by fluid-pressure means (not shown) to carry the upper-trimming means toward the wipers prior to its action on the upper. Such downward movement of the post is limited by a stop member 98 which is adjustable upwardly and downwardly under the lower end of the post by means fully described in the previously mentioned application. This adjustment is such as to position the cutting edges of the knives 86 and 88, when they operate on the upper, in a plane spaced from the top faces of the wipers a distance substantially equal to the thickness of the outer layer of the upper materials, so that the knives, moving in directions parallel to those faces, will remove the other layers while leaving the margin of the outer layer to be wiped inwardly over the insole. In accordance with the disclosure of Letters Patent No. 2,337,558, granted on December 28, 1943, on an application of mine, and also with the disclosure of the previously mentioned application, provision is afforded after the upper-trimming operation for the gripping and pulling of the upper a second time by the grippers, in engagement at this time only with the outer layer of the upper materials, and for the wiping of the upper heightwise of the last a second time by the toe former coordinately with the second pull on the upper (Fig. 9). In proper time relation to these operations the carrier 94 is moved upwardly to carry the upper-trimming means away from the shoe and is swung about the axis of the post 96 to carry cement-applying means 100, also supported thereon, to a position over the toe end of the shoe, after which the carrier is moved downwardly to carry the cement-applying means into engagement with the insole and to apply cement thereto. Thereafter the margin of the upper is wiped inwardly

over the insole by the wipers 74 into position to be secured to the insole by the cement.

In general accordance with the disclosure of Letters Patent No. 2,479,575, the wiper support 32 is moved upwardly to carry the wipers and the toe former heightwise of the shoe as above described by a pair of pistons 102 (Fig. 2) vertically movable in cylinders 104 fast on the frame of the machine, the pistons being moved upwardly by fluid admitted to the lower ends of the cylinders. The pistons 102 are arranged to act respectively on the opposite side portions of the wiper support through connections which, for a purpose hereinafter described, are herein shown as differently constructed at the opposite sides of the support respectively. Associated with the left-hand piston 102 is a link 106 (Fig. 6) pivotally mounted on a pin 108 in the wiper support and provided at its lower end with a slot 110 through which extends a pin 112 mounted in an upward extension of the piston. Associated with the right-hand piston is a differently formed link 114 (Fig. 5) fast on a shaft 116 in the wiper support and provided with a slot 118 through which extends a pin 120 mounted in an upward extension of the piston. Disregarding for the moment the differences between the links 106 and 114, it may be stated that as the pistons 102 are moved upwardly the pins 112 and 120 engage the respective links 106 and 114 and thereby raise the wiper support, these movements of the pistons being limited by means hereinafter described. When the wipers are operated to wipe the margin of the upper inwardly over the insole, the slots in the links permit the wiper support and the parts thereon to be moved independently of the pistons somewhat farther against the force of gravity in response to resistance of the margin of the upper to the movements of the wipers, so that the wipers will not act too severely on portions of the margin of the upper in wiping it inwardly, especially if the bottom of the toe end of the last has a convex curvature.

After the wipers have wiped the margin of the upper inwardly, it is desirable to increase their downward pressure thereon. For this purpose, in accordance with the disclosure of the last-mentioned Letters Patent, the upper portions of the pistons 102 are of reduced diameter and are slidably movable in sleeves 122 which are secured to the upper ends of the cylinders 104 and extend downwardly within the cylinders, the sleeves having thereon upwardly extending lugs 124 which engage the pins 112 and 120 to limit downward movements of the pistons. Between the lower end of each sleeve and the larger portion of the piston 102 is an annular chamber 125 into which fluid is admitted at the proper time from a pipe line 126 (Fig. 11) under control of a valve 127 to cause the wipers to apply increased downward pressure on the margin of the upper, the lower ends of the cylinders at this time being open to exhaust. In this operation the pins 112 and 120 act on the links 106 and 114 at the lower ends of the slots in the links. Before the wipers are withdrawn from over the shoe bottom the pressure is terminated in the chambers 125 and is applied again below the pistons to relieve the pressure of the wipers on the margin of the upper. After the wipers have been withdrawn the lower ends of the cylinders are again opened to exhaust to cause the wiper support to be lowered by gravity. To limit the upward movements of the pistons, including the movements whereby they relieve the pressure of the wipers on the up-

per as above described, their reduced portions have thereon flanges 123 of slightly smaller diameter than the interior of the cylinders for engaging the lower ends of the sleeves 122. It may be further stated that, in accordance with the disclosure of the previously mentioned application, the machine herein shown is provided with means for partially counterbalancing in a yieldable manner the weight of the wiper support 82 and the parts thereon when the wipers wipe the margin of the upper inwardly over the insole, such means including pins 130 subjected through springs 131 to pressure of the fluid in the lower ends of the cylinders 104 and arranged to engage the lower ends of the links 106 and 114.

Machines such as that to which the invention is herein shown as applied have heretofore been so constructed and adjusted that, as the result of the upper-trimming operation, a margin of about an eighth of an inch in width has been left on the inner layers of the upper materials to overlap the bottom face of the edge portion of the insole when the wipers are moved inwardly. That is, the upward movement of the wiper support 82 has been so limited relatively to the position of the shoe that the top faces of the wipers have been positioned in the upper-trimming operation at the proper distance higher than the edge of the toe end of the insole to cause the upper-trimming means, when properly adjusted relatively to the wipers, to leave a margin of that width on the inner layers of the upper materials beyond the edge of the insole. When the wipers are thereafter moved upwardly again to the same height in time relation to the second pull applied to the upper by the grippers, they are in the proper relation to the edge of the insole to wipe the upper inwardly over the insole. Some manufacturers, however, prefer that a margin of somewhat greater width be left on the inner layers of the upper materials to overlap the insole, although still of considerably less width than the inwardly wiped margin of the outer layer of the materials. If the wipers are moved upwardly the first time to such a height as to provide for such increased width of margin on the inner layers, they should not be moved to the same height the second time, since in that case they would be too high relatively to the edge of the insole to wipe the upper most effectively inward over the insole. The machine herein shown is accordingly provided with means whereby the wiper support 82 is moved upwardly the first time to position the wipers at the proper height to cooperate with the trimming means in providing a margin of the increased width on the inner layers, but is moved upwardly the second time to a position a little lower than the limit of its first upward movement to position the wipers in proper relation to the shoe for wiping the upper inwardly over the insole. For this purpose the slot 118 in the link 114 associated with the right-hand piston 102 is so formed that the upper wall of the slot has a rear portion *a* which is stepped upward a short distance relatively to a front portion *b* thereof. Initially the portion *b* is engaged by the pin 120, and by such engagement the wiper support is moved upwardly to the greater height required for the trimming of the upper in the manner above described. The slot 110 in the link 106 associated with the left-hand piston 102 is so arranged that initially the pin 112 is slightly below the upper end of the slot, as shown in Fig. 6, thus providing for lost motion before the left-hand piston becomes effective in

raising the wiper support. When the two pistons 102, moreover, are at the limits of their upward movements the pin 112 is positioned the same distance as initially below the upper end of the slot in the link 106, the right-hand piston alone, therefore, being effective on the wiper support at the end of the upward movement of the support. To cause the wiper support to be moved upward the second time to a position short of the limit of its first upward movement, the link 114 is swung in a clockwise direction with reference to Fig. 5 to position the stepped-up wall *a* of the slot 118 over the pin 120. For this purpose there is pivotally mounted for swinging movement about a pin 132 in a fixed casting 134 a latch 136 held initially by a spring 138 in a position determined by its engagement with a shoulder 140 on the casting. After the first upward movement of the wiper support but prior to its second upward movement this latch is swung against the resistance of the spring to a position in which its upper end is over a roll 142 mounted on a rearwardly extending arm 144 which is fast on the shaft 116 to which the link 114 also is secured. This movement of the latch is effected by a piston 146 mounted in a cylinder 148 formed in the casting 134, the rounded front end of the piston engaging the latch. Conveniently the cylinder 148 is in communication with a pipe line leading to means, not herein shown, for swinging the carrier 94 (Fig. 1) to carry the upper-trimming means away from over the shoe, since this movement of the carrier takes place at the time when it is desired to operate the latch. The latch having been swung to a position over the roll 142, it serves to swing the link 114 as above described in response to the second upward movement of the wiper support. The link is thus swung against the resistance of a return spring 150 connected at its lower end to the arm 144 and at its upper end (Fig. 2) to a clip 152 secured to the wiper support. By reason of the stepped-up position of the portion *a* of the wall of the slot 118 the pin 112 carried by the left-hand piston 102 is also effective on the link 106 associated therewith substantially throughout the second upward movement of the wiper support.

Pivotedly connected at its rear end to the latch 136 is a link 154 provided in its front end with a slot 156 into which extends a pin 158 mounted in a lever 160, this lever being mounted to swing about a pin 162 supported by one of the cylinder castings 104. Connected to the lever is a spring 164 which under the conditions illustrated holds it in a position determined as hereinafter described. Connected to the upper end of the lever is a latch 166 extending forwardly through an opening 168 in the frame of the machine and having a hook-shaped front end by which the operator may swing the upper arm of the lever 160 in a forward direction against the resistance of the spring 164, the latch being provided with a shoulder 170 arranged to engage a plate 172 on the frame to hold the lever in the position to which it is thus moved by the operator. By its forward swinging movement the upper arm of the lever acts through the link 154 to swing the latch 136 to a position over the roll 142, in which position the latch 136 remains as long as the lever 160 is held by the latch 166. The link 114, therefore, is swung by the latch 136 in the manner above described in response to every upward movement of the wiper support, and accordingly the wipers are moved upward the first time only to the same height as the second time. It

will be evident that under these conditions the upper-trimming means 84 must occupy in the upper-trimming operation a correspondingly lower position in order to cooperate properly with the wipers in trimming the upper, thereby providing a margin of less width beyond the edge of the insole on the inner layers of the upper materials. Provision is therefore afforded for determining, by the movement of the lever 160, a lower limit of downward movement of the carrier 94 which supports the upper-trimming means. Supported on the top of the stop member 98 (Figs. 1 and 7), previously described as arranged to engage the lower end of the post 96 to limit downward movement of the carrier 94, is an auxiliary stop member 174 pivotally mounted to swing about a stud 176 into or out of position for limiting engagement with the lower end of the post. As shown in Fig. 7 the auxiliary stop member is in position thus to engage the post, this being its position when the wipers are moved to the greater height and the trimming means acts to provide a margin of greater width on the inner layers of the upper materials. Pivotally connected to the lower end of the lever 160 is a rearwardly extending link 178 which is pivotally connected at its rear end to an arm 180 fast on a short vertical shaft 182 rotatable in the frame, this shaft having also fast thereon an arm 184 pivotally connected to one end of a link 186 the other end of which is pivotally connected to an arm 188 on the auxiliary stop member 174. When the lever 160 is swung to the position determined by the latch 166 it acts through the connections described to swing the auxiliary stop member 174 to an idle position where it will have no effect on the post 96, so that the downward movement of the carrier 94 will be limited by engagement of the post with the stop member 98 and the upper-trimming means will occupy in the upper-trimming operation a lower position corresponding to the lower position of the wipers at that time. When the auxiliary stop member 174 is in its operative position it engages a member 190 which is part of a ball bearing shown in the previously mentioned application as resting on the stop member 98, the member 190 accordingly limiting the movement of the lever 160 under the influence of the spring 164. When the lever 160 is in the position shown it is not disturbed by the movement of the latch 136 by the piston 146 by reason of the slot 156 in the link 154. The movement of the latch by the piston is limited by engagement of a projection 192 on its lower end with a top face of the casting 134. Located above the auxiliary stop member 174 is another similar stop member 194 which is also mounted to swing about the stud 176 and in accordance with the disclosure of the previously mentioned application may, if desired, be swung to a position under the post 96 to prevent the upper-trimming means from being carried downwardly far enough to operate on a shoe.

To facilitate the return of the link 114 by the spring 150 in response to each downward movement of the wiper support 82 after the action of the latch 136 on the link, there is threaded in a member 196 carried by the wiper support a screw 198 the head of which is arranged to engage the left-hand cylinder casting 104 and thereby to limit the downward movement of the wiper support. This screw is so adjusted that when the wiper support is at the limit of its downward movement the pin 120 is only lightly in contact with the portion *b* of the upper wall of the slot 75

118, the screw serving to relieve the pin from such pressure of the link thereon as might cause the pin to bind on the portion *b* of the wall and thereby prevent the full return of the link by the

5 spring.

It will be evident that the greater upward movement of the wiper support the first time than the second time extends and increases the wiping effect of the toe former 76 on portions of the 10 upper adjacent to the extreme edge of the insole. This has been found to contribute appreciably to the smoothness of the upper in this location in the completed shoe.

Associated with the right-hand piston 102 is 15 mechanism, including a spring 200 (Fig. 1), for supplementing the pressure of the fluid in forcing the wipers more firmly down on the overwiped margin of the upper, this mechanism being provided to permit a variation in the force thus applied by the wipers to the upper. This mechanism is of the same construction as disclosed in Letters Patent No. 2,479,575, and therefore will not be described in detail. In the construction herein shown additional means is provided for 20 effecting a further variation in the downward pressure applied by the wipers to the upper. For this purpose the pipe line 126 (Fig. 11) is so arranged as to conduct fluid from the manifold always to the chamber 125 in the left-hand cylinder 104 when the valve 127 is operated, but has 25 therein a valve 202 which may be rotated by a handle 204 to a position such as to prevent flow of the fluid to the chamber 125 in the right-hand cylinder. With the valve in the position shown there is a passage for the fluid to this chamber as well as to the chamber in the left-hand cylinder, but it will be evident that upon rotation of the valve in a clockwise direction with 30 reference to Fig. 11 through an arc of 90° flow of the fluid to the chamber in the right-hand cylinder will be interrupted and this chamber will be put in communication with a pipe 206 leading to the sump 18. Accordingly, the wipers may be 35 forced downwardly on the margin of the upper by the force of the fluid acting on both pistons 102 or on one of the pistons alone. It will be 40 understood that this controlling means does not prevent such further more precise variation in the pressure applied to the upper by the wipers as may be effected by the above-mentioned mechanism including the spring 200.

Having regard only to the construction thus far described, it will be evident that when the pistons 102 are moved upwardly to relieve the pressure 45 of the wipers on the overwiped margin of the upper, after having been forced downwardly to increase this pressure, no actual lifting of the wipers by the pistons can take place until after one, at least, of the pins 112, 120 has engaged 50 the corresponding link 106 or 114 at the upper end of the slot formed in the link, and that in any event the wipers will not be raised beyond the 55 positions occupied at the beginning of the wiping operation, in which they are shown in Fig. 9 since the portion *a* of the wall of the slot 118 will at 60 this time be over the pin 120. The machine herein shown is provided with means whereby the wipers are raised to a higher plane than in Fig. 9 prior to their retractive movements from over 65 the shoe bottom, thus substantially or completely releasing the overwiped margin of the upper from the pressure of the wipers thereon. For the purpose in view a bracket 208 is secured on the front of the left-hand portion of the wiper support 82 and has pivotally mounted thereon a

lever 210 one arm of which is provided with a lug 212 extending upwardly to a position in front of the forwardly and rearwardly movable wiper carrier 80 and a portion of the other arm of which extends rearwardly and is provided with a downwardly extending lug 214 arranged to engage the left-hand end of the pin 112 carried by the left-hand piston 102, as illustrated in Fig. 2. Extending forwardly from the wiper carrier 80 through an opening in the lug 212 is a rod 216, and mounted on this rod between the wiper carrier and the lug is a spring 218 which is compressed by the forward movement of the wiper carrier in operating the wipers. Through this spring, therefore, the lug 214 on the left-hand arm of the lever 210 is pressed against the left-hand end of the pin 112. Formed in this end of the pin is a notch 220, and when the left-hand piston is moved downwardly to increase the pressure of the wipers on the upper the downward movement of the pin 112 along the slot 110 (Fig. 6) in the link 106 before the piston becomes effective on the wipers causes the lug 214 on the lever 210 to enter the notch 220 in the pin. When the left-hand piston 102, therefore, is moved upwardly to relieve the pressure of the wipers on the upper there is substantially no lost motion of the pin 112 in the slot 110, the pin acting through the lever 210 on the wiper support to impart to the support an upward movement substantially equal to the upward movement of the piston before the piston is stopped by the sleeve 122. The wipers, therefore, are raised to positions such as to apply substantially no pressure to the upper, as illustrated in Fig. 10. An important advantage of this will be understood from the fact that the timing of the valve 26 is, as heretofore, such as to release the fluid from the cylinder 8 and thus to cause return movement of the toe rest 4 prior to the retractive movements of the wipers from over the shoe. It has already been explained that any force applied to the shoe tending to press the shoe more firmly on the toe rest tends to hold the cut-off valve 58 of the pressure-controlling means 44 associated with the toe rest more firmly closed. Unless the shoe, therefore, is substantially released from the downward pressure of the wipers thereon before the valve 26 is moved to exhaust position, the cut-off valve 58 may not open and release the fluid from the cylinder 8 notwithstanding such movement of the valve 26. Raising of the wipers in the manner described insures the prompt withdrawal of the toe rest at the time intended. When the wiper carrier 80 moves rearwardly to retract the wipers, a head 222 on the rod 216 engages the lug 212 near the end of that movement of the carrier and thus withdraws the lug 214 on the lever 210 from the notch 220 in the pin 112.

Also secured to the front of the left-hand portion of the wiper support 82 is a bar 224 in which is mounted a screw 226 in position to engage the wiper carrier 80 and thereby to limit the forward movement of the carrier. This screw, therefore, serves to determine adjustably the limits of the inward movements of the wipers over the shoe both lengthwise and widthwise of the shoe.

Since the manner of operation of the mechanisms described has already been fully explained in connection with the description of the mechanism, no further description of the operation of the machine is necessary.

Having described the invention, what I claim

as new and desire to secure by Letters Patent of the United States is:

1. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper inwardly over the insole, a wiper support movable to carry the wipers heightwise of the last past the edge of the insole into positions thus to support the margin of the upper for the upper-trimming operation, and power-operated means for thus moving said wiper support prior to the upper-trimming operation and for thereafter automatically moving it again in the same direction heightwise of the last to a position short of the limit of its first movement to carry the wipers into positions for wiping the upper inwardly over the insole.
2. In a lasting machine, wipers for wiping the margin of an upper around the toe end of a last inwardly over an insole on the last, upper-trimming means arranged to remove from the margins of the upper supported in outspread position on said wipers all but the outer layer of the upper materials prior to the wiping of the upper inwardly over the insole, a wiper support movable to carry the wipers heightwise of the last past the edge of the insole into positions thus to support the margin of the upper for the upper-trimming operation, an operating member for thus moving the wiper support prior to the upper-trimming operation and for thereafter moving it a second time in the same direction heightwise of the last to carry the wipers into positions for wiping the upper inwardly over the insole, and means for automatically terminating the second movement of the wiper support short of the limit of its first movement.
3. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper inwardly over the insole, a wiper support movable to carry the wipers heightwise of the last past the edge of the insole into positions thus to support the margin of the upper for the upper-trimming operation, an operating member having a predetermined limit of movement thus to move the wiper support prior to the upper-trimming operation and thereafter to move it a second time in the same direction heightwise of the last to carry the wipers into positions for wiping the upper inwardly over the insole, and means for automatically terminating the second movement of the wiper support short of the limit of its first movement regardless of the limit of movement of said operating member.
4. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper inwardly over the insole, a wiper support movable to carry the wipers heightwise of the last past the edge of the insole into positions thus to support the margin of the upper for the upper-trimming operation, an operating member having

a predetermined limit of movement thus to move the wiper support prior to the upper-trimming operation and thereafter to move it a second time in the same direction heightwise of the last to carry the wipers into positions for wiping the upper inwardly over the insole, means for transmitting movement to the wiper support from said operating member, said transmitting means including a device shiftable into position to terminate the second movement of the wiper support short of the limit of its first movement, and means for thus shifting said device.

5. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper inwardly over the insole, a wiper support movable to carry the wipers heightwise of the last past the edge of the insole into positions thus to support the margin of the upper for the upper-trimming operation, an operating member having a predetermined limit of movement thus to move the wiper support prior to the upper-trimming operation and thereafter to move it a second time in the same direction heightwise of the last to carry the wipers into positions for wiping the upper inwardly over the insole, means for transmitting movement to the wiper support from said operating member, said transmitting means including a device having a slot therein so formed as to terminate the second movement of the wiper support short of the limit of its first movement in consequence of shifting movement of the device from one position to another position, and means for thus shifting said device prior to the completion of the second movement of the wiper support.

6. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper inwardly over the insole, a wiper support movable to carry the wipers heightwise of the last past the edge of the insole into positions thus to support the margin of the upper for the upper-trimming operation, an operating member having a predetermined limit of movement thus to move the wiper support prior to the upper-trimming operation and thereafter to move it a second time in the same direction heightwise of the last to carry the wipers into positions for wiping the upper inwardly over the insole, means for transmitting movement to the wiper support from said operating member, said transmitting means including a link mounted for swinging movement and having therein a slot so formed as to terminate the second movement of the wiper support short of the limit of its first movement in consequence of swinging movement of the link from one position to another position, and means for thus swinging the link in response to the second movement of the wiper support.

7. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper

inwardly over the insole, a wiper support movable to carry the wipers heightwise of the last past the edge of the insole into positions thus to support the margin of the upper for the upper-trimming operation, a fluid-operated piston having a predetermined limit of movement thus to move the wiper support prior to the upper-trimming operation and thereafter to move it a second time in the same direction heightwise of the last to carry the wipers into positions for wiping the upper inwardly over the insole, a pin carried by said piston, a link carried by the wiper support and having a slot into which said pin extends for transmitting movement from the piston to the wiper support, said slot being so formed as to terminate the second movement of the wiper support short of the limit of its first movement in consequence of movement of the link relatively to the pin from one position to another position, and means for thus moving the link after the first movement of the wiper support.

8. In a lasting machine, wipers for wiping the margin of an upper around the toe end of a last positioned bottom upward inwardly over an insole on the last, upper-trimming means movable in a plane parallel to the top faces of said wipers to remove from the margin of the upper supported in outspread position on said faces less than the entire thickness of the upper materials prior to the wiping of the upper inwardly over the insole, a wiper support mounted for upward movement relatively to the upper-trimming means to carry the wipers into positions thus to support the margin of the upper for the upper-trimming operation, and means for thus moving said wiper support prior to the upper-trimming operation and for thereafter moving it upwardly again to a position short of the limit of its first upward movement to carry the wipers into positions for wiping the upper inwardly over the insole.

9. In a lasting machine, wipers for wiping the margin of an upper around the toe end of a last positioned bottom upward inwardly over an insole on the last, upper-trimming means movable in a plane parallel to the top faces of said wipers to remove from the margin of the upper supported in outspread position on said faces less than the entire thickness of the upper materials prior to the wiping of the upper inwardly over the insole, a wiper support mounted for upward movement to carry the wipers into positions thus to support the margin of the upper for the upper-trimming operation, an operating member having a predetermined limit of movement thus to move the wiper support prior to the upper-trimming operation and thereafter to move it upwardly again to carry the wipers into positions for wiping the upper inwardly over the insole, and means for automatically terminating the second upward movement of the wiper support short of the limit of its first upward movement regardless of the limit of movement of said operating member.

10. In a lasting machine, wipers for wiping the margin of an upper around the toe end of a last positioned bottom upward inwardly over an insole on the last, upper-trimming means movable in a plane parallel to the top faces of said wipers to remove from the margin of the upper supported in outspread position on said faces less than the entire thickness of the upper materials prior to the wiping of the upper inwardly over the insole, a wiper support mounted for upward movement to carry the wipers into positions thus

to support the margin of the upper for the upper-trimming operation, an operating member having a predetermined limit of movement thus to move the wiper support prior to the upper-trimming operation and thereafter to move it upwardly a second time to carry the wipers into positions for wiping the upper inwardly over the insole, means for transmitting movement to the wiper support from said operating member, said transmitting means including a device shiftable into position to terminate the second movement of the wiper support short of the limit of its first movement, and automatic means for thus shifting said device after the first upward movement of the wiper support.

11. In a lasting machine, wipers for wiping the margin of an upper around the toe end of a last positioned bottom upward inwardly over an insole on the last, upper-trimming means movable in a plane parallel to the top faces of said wipers to remove from the margin of the upper supported in outspread position on said faces less than the entire thickness of the upper materials prior to the wiping of the upper inwardly over the insole, a wiper support mounted for upward movement to carry the wipers into positions thus to support the margin of the upper for the upper-trimming operation, an operating member having a predetermined limit of movement thus to move the wiper support prior to the upper-trimming operation and thereafter to move it upwardly a second time to carry the wipers into positions for wiping the upper inwardly over the insole, means for transmitting movement to the wiper support from said operating member, said transmitting means including a device having a slot therein so formed as to terminate the second upward movement of the wiper support short of the limit of its first upward movement in consequence of shifting of the device from one position to another position, a member for thus shifting said device in response to the second upward movement of the wiper support, and means for moving said last-named member into position thus to act on said device after the first upward movement of the wiper support.

12. In a lasting machine, wipers for wiping the margin of an upper around the toe end of a last inwardly over an insole on the last, upper-trimming means arranged to remove from the margin of the upper supported in outspread position on said wipers less than the entire thickness of the upper materials prior to the wiping of the upper inwardly over the insole, a wiper support movable to carry the wipers heightwise of the last past the edge of the insole into positions thus to support the margin of the upper for the upper-trimming operation, means for thus moving said wiper support prior to the upper-trimming operation and for thereafter moving it a second time in the same direction heightwise of the last to a position short of the limit of its first movement to carry the wipers into positions for wiping the upper inwardly over the insole, and means for alternatively terminating the first movement of the wiper support when the wipers are in the same positions as at the end of its second movement.

13. In a lasting machine, wipers for wiping the margin of an upper around the toe end of a last inwardly over an insole on the last, upper-trimming means movable in a plane parallel to said wipers to remove from the margin of the upper supported in outspread position on the wipers less than the entire thickness of the upper ma-

terials prior to the wiping of the upper inwardly over the insole, a wiper support movable relatively to said upper-trimming means to carry the wipers heightwise of the last past the edge of the insole into positions thus to support the margin of the upper for the upper-trimming operation, means for thus moving said wiper support prior to the upper-trimming operation and for thereafter moving it again in the same direction heightwise of the last to a position short of the limit of its first movement to carry the wipers into positions for wiping the upper inwardly over the insole, means for alternatively terminating the first movement of the wiper support when the wipers are in the same positions as at the end of its second movement, and means for differently positioning said upper-trimming means heightwise of the last when the first movement of the wiper support is thus alternatively terminated.

14. In a lasting machine, wipers for wiping the margin of an upper around the toe end of the last inwardly over an insole on the last, upper-trimming means movable in a plane parallel to the wipers to remove from the margin of the upper supported in outspread position on the wipers less than the entire thickness of the upper materials prior to the wiping of the upper inwardly over the insole, said upper-trimming means being movable heightwise of the last into position for the upper-trimming operation, a wiper support movable relatively to said upper-trimming means to carry the wipers heightwise of the last past the edge of the insole into positions thus to support the margin of the upper for the upper-trimming operation, means for thus moving said wiper support prior to the upper-trimming operation and for thereafter moving it a second time in the same direction heightwise of the last to a position short of the limit of its first movement to carry the wipers into positions for the wiping of the upper inwardly over the insole, a member optionally movable into position to cause the first movement of the wiper support to terminate at the same limit as its second movement, and means controlled by said member for differently limiting the movement of the upper-trimming means heightwise of the last when the first movement of the wiper support is thus terminated.

15. In a lasting machine, wipers for wiping the margin of an upper around the toe end of a last positioned bottom upward inwardly over an insole on the last, upper-trimming means movable in a plane parallel to the top faces of said wipers to remove from the margin of the upper supported in outspread position on said faces less than the entire thickness of the upper materials prior to the wiping of the upper inwardly over the insole, a wiper support mounted for upward movement to carry the wipers into positions thus to support the margin of the upper for the upper-trimming operation, an operating member having a predetermined limit of movement thus to move the wiper support prior to the upper-trimming operation and thereafter to move it upwardly a second time to carry the wipers into positions for wiping the upper inwardly over the insole, means for transmitting movement to the wiper support from said operating member, said transmitting means including a device so formed as to terminate the second upward movement of the wiper support short of the limit of its first upward movement in consequence of shifting of the device from one position to another position, a member for thus shifting said device only in

response to the second upward movement of the wiper support, and means for optionally causing said member to shift said device also in response to the first upward movement of the wiper support to terminate that movement when the wipers are in the same positions as at the end of the second upward movement of the support.

16. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper inwardly over the insole, a wiper support movable to carry the wipers heightwise of the last past the edge of the insole into positions thus to support the margin of the upper for the upper-trimming operation, means for thus moving said wiper support prior to the upper-trimming operation and for thereafter moving it a second time in the same direction heightwise of the last to a position short of the limit of its first movement to carry the wipers into positions for wiping the upper inwardly over the insole, and a toe former carried by said wiper support for wiping the upper heightwise of the last a greater distance in response to the first movement of the support than in response to its second movement.

17. In a lasting machine, wipers for wiping the margin of an upper around the toe end of a last inwardly over an insole on the last, upper-trimming means arranged to remove from the margin of the upper supported in outspread position on said wipers all but the outer layer of the upper materials prior to the wiping of the upper inwardly over the insole, upper-gripping means for gripping the margin of the upper and pulling it outwardly over the wipers prior to the upper-trimming operation and for similarly gripping and pulling the margin of the outer layer only after the upper-trimming operation, a support for said wipers, means for moving said wiper support to carry the wipers heightwise of the last while the upper-gripping means is applying the first pull to the upper and for moving it a second time in the same direction heightwise of the last to a position short of the limit of its first movement while the upper-gripping means is applying the second pull to the upper, and a toe former carried by said wiper support for wiping the upper heightwise of the last a greater distance in response to the first movement of the support than in response to its second movement.

18. In a lasting machine, wipers for wiping the margin of an upper around the toe end of a last positioned bottom upward inwardly over an insole on the last, a support for said wipers mounted for movements to carry them upwardly and downwardly, means including an operating member movable in opposite directions respectively to raise said wiper support to carry the wipers into positions for wiping the upper inwardly over the insole and thereafter to move it downwardly to increase the pressure of the wipers on the overwiped margin of the upper, said operating member being thereafter movable in the same direction as in raising the wiper support to relieve the downward pressure of the wipers on the upper, means for positively limiting the movement of said member in the direction to raise the wiper support, a lost-motion connection between said member and the wiper support to permit the wipers to be moved farther upwardly relatively to said member in response to resistance of the

upper as it is wiped inwardly over the insole, and means for substantially eliminating lost motion between said member and the wiper support in the movement of said member to relieve the pressure of the wipers on the upper and for thus causing the wipers to be lifted by said member.

19. In a lasting machine, wipers for wiping the margin of an upper around the toe end of a last positioned bottom upward inwardly over an insole on the last, a support for said wipers mounted for movements to carry them upwardly and downwardly, means including an operating member movable in opposite directions respectively to raise said wiper support to carry the wipers into positions for wiping the upper inwardly over the insole and thereafter to move it downwardly to increase the pressure of the wipers on the overwiped margin of the upper, said operating member being thereafter movable in the same direction as in raising the wiper support to relieve the downward pressure of the wipers on the upper, means for positively limiting the movement of said member in the direction to raise the wiper support, a lost-motion connection between said member and the wiper support to permit the wipers to be moved farther upwardly relatively to said member in response to resistance of the upper as it is wiped inwardly over the insole, a device mounted for movement into position substantially to eliminate lost motion between said member and the wiper support in the movement of said member to relieve the pressure of the wipers on the upper, and means for thus moving said device in response to the movement of said member in the direction to increase the pressure of the wipers on the upper.

20. In a lasting machine, wipers for wiping the margin of an upper around the toe end of a last positioned bottom upward inwardly over an insole on the last, a support for said wipers mounted for movements to carry them upwardly and downwardly, means including a piston movable in opposite directions respectively by fluid pressure to raise said wiper support to carry the wipers into positions for wiping the upper inwardly over the insole and thereafter to move it downwardly to increase the pressure of the wipers on the overwiped margin of the upper, said piston being thereafter movable in the same direction as in raising the wiper support to relieve the downward pressure of the wipers on the upper, means for positively limiting the movement of the piston in the direction to raise the wiper support, a pin-and-slot connection between said piston and the wiper support to provide for lost motion to permit the wipers to be moved farther upwardly relatively to the piston in response to resistance of the upper as it is wiped inwardly over the insole, and means for substantially eliminating the lost motion provided by said pin-and-slot connection in the movement of the piston to relieve the pressure of the wipers on the upper and for thus causing the wipers to be lifted by the piston.

21. In a lasting machine, wipers for wiping the margin of an upper around the toe end of a last positioned bottom upward inwardly over an insole on the last, a support for said wipers mounted for movements to carry them upwardly and downwardly, means including a piston movable in opposite directions respectively by fluid pressure to raise said wiper support to carry the wipers into positions for wiping the upper inwardly over the insole and thereafter to move it downwardly to increase the pressure of the

21

wipers on the overwiped margin of the upper, said piston being thereafter movable in the same direction as in raising the wiper support to relieve the downward pressure of the wipers on the upper, means for positively limiting the movement of the piston in the direction to raise the wiper support, a pin carried by said piston, means on said wiper support having a slot into which said pin extends to provide for lost motion between the piston and the wiper support and thereby to permit the wipers to be moved farther upward relatively to the piston in response to resistance of the upper as it is wiped inwardly over the insole, a member carried by the wiper support and mounted for movement into such relation to said pin as substantially to eliminate lost motion between the piston and the wiper support in the movement of the piston to relieve the pressure of the wipers on the upper, and means for thus moving said member in response to the movement of the piston in the direction to increase the pressure of the wipers on the upper.

22. In a lasting machine, wipers for wiping the margin of an upper around the toe end of a last positioned bottom upward inwardly over an insole on the last, a support for said wipers mounted for movements to carry them upwardly and downwardly, a wiper carrier mounted on said wiper support for movement to operate the wipers, means including a piston movable in opposite directions respectively to raise said wiper support to carry the wipers into positions for wiping the upper inwardly over the insole and thereafter to move it downwardly to increase the pressure of the wipers on the overwiped margin of the upper, said piston being thereafter movable in the same direction as in raising the wiper support to relieve the downward pressure of the wipers on the upper, means for positively limiting the movement of the piston in the direction to raise the wiper support, a lost-motion connection between the piston and the wiper support to permit the wipers to be moved farther upward relatively to the piston in response to resistance of the upper as it is wiped inwardly over the insole, a member carried by the wiper support and mounted for movement into position substantially to eliminate lost motion between the piston and the wiper support in the movement of the

22

5 piston to relieve the pressure of the wipers on the upper, and a spring arranged to be subjected to stress by the movement of said wiper carrier thus to move said member in response to the movement of the piston in the direction to increase the pressure of the wipers on the upper.

10 23. In a lasting machine, lasting means for lasting the margin of the upper of a shoe on a last inwardly over an insole on the last and for pressing it heightwise of the last on the insole, a toe rest arranged to engage the shoe on the top of the forepart and to support it against the pressure of said lasting means thereon, a source of fluid under pressure, fluid-pressure means for forcing said toe rest against the shoe, a valve for admitting fluid from said source to said fluid-pressure means and for thereafter releasing the fluid therefrom, pressure-controlling mechanism between said valve and said fluid-pressure means for variably predetermining the pressure of the fluid effective on said toe rest independently of the pressure of the fluid at said source, said pressure-controlling mechanism including a cut-off valve and a member subject to the pressure of the fluid effective on the toe rest for closing said cut-off valve when that pressure reaches a predetermined limit, said member being arranged to hold the cut-off valve more firmly close in response to the pressure applied to the shoe heightwise thereof by said lasting means, and mechanism for substantially releasing the shoe from any pressure of said lasting means thereon and for thereby freeing the cut-off valve from the influence of such pressure prior to retractive movement of said lasting means from over the shoe.

BERNHARDT JORGENSEN.
